UNITED STATES PATENT OFFICE

JOSEPH GARDNER AND JOSEPH HUGH STOTT GARDNER, OF PATRICROFT, NEAR MANCHESTER, ENGLAND, ASSIGNEES TO L. GARDNER & SONS LIMITED, OF PATRICROFT, NEAR MANCHESTER, ENGLAND, A BRITISH COMPANY

VALVE OPERATING MECHANISM OF INTERNAL COMBUSTION ENGINES

Application filed August 30, 1929, Serial No. 389,485, and in Great Britain January 4, 1929.

This invention relates to internal combustion engines of the compression ignition type. It is usual to time the inlet valves of such engines so that they close considerably after the end of the suction stroke and for normal running conditions this arrangement has advantages but at starting when the engine is turned at a comparatively low rate usually by compressed air, the late closing of the inlet valve reduces the effective compression ratio and therefore the compression pressure and the compression temperature.

It is known to vary the timing of the inlet valve operating cam relatively to the engine crank shaft at starting but such variation whilst it makes the time of closing earlier results in the valve opening too soon with corresponding disadvantages.

In accordance with our present invention, we provide means for shortening the period of opening of the inlet valve so that at starting the full stroke of the piston is obtained for compression purposes, without the necessity for a too early opening of the inlet valve.

Referring to the accompanying explanatory drawings:—

Figure 1 is an elevation with a part in section, Figure 2 a sectional elevation at right angles to Figure 1, and Figure 3 a plan view with the cover removed, of inlet valve operating means constructed and arranged in one convenient form in accordance with our invention.

Figure 4 is a detail view illustrating the end of the valve rocker which engages the inlet valve stem.

The same reference letters in the different views indicate the same parts.

We arrange the rocker *a* which operates the inlet valve *b* and which is itself operated by the usual push rod *c*, with two faces *d*, *e* either of which can be caused to engage the valve stem by a suitable lateral displacement of the rocker along its shaft *f* against the pressure of the spring *g*. The operative face *d* of the rocker provides for a minimum clearance between the valve stem *c* and itself and is for normal running conditions with the inlet valve closing considerably after the end of the suction stroke, whilst the operative face

e provides for a relatively considerable clearance so that the inlet valve *b* opens later and closes earlier. The lateral movement of the rocker *a* is effected by a scroll or face cam *h* which engages the side of the rocker at 55 and is operated by a handle *j* upon a spindle *k* carrying such face cam.

The spindle *k* carrying said face cam *h* and handle *j* is cut away at two points *m*, *n* so that when the handle *j* is turned to bring either of said cut away portions beneath the rocker *a*, the rocker can move to its full extent as determined by the push rod *c*, but when the shaft *k* is turned to bring the portion of the spindle which is not cut away beneath the rocker, the latter is prevented from following up the push rod *c* as it is withdrawn to allow the valve *b* to close; such valve is therefore held open and acts as a compression relief means. In the position 70 of the operating handle shown at X, Figure 2, the cam *h* is clear of the rocker *a* and the cut away portion *m* of the spindle *k* is beneath the rocker so that the latter operates the valve in a normal manner; in a second 75 position as indicated at Y, Figure 2, the face cam *h* is still clear of the rocker but the spindle *k* is preventing the rocker from moving to its full extent to close the valve *b*—this is the compression relief position; in the third 80 position of the handle shown at Z, Figure 2, the face cam *h* has moved the rocker to bring the end *e* into operation and the cut away portion *n* of the spindle *k* is beneath the rocker *a*—this is the starting position. 85

Our improvement is particularly advantageous for use with high speed engines of the compression ignition type.

What we claim is:—

1. In internal combustion engines of the compression ignition type, the combination with the inlet valve, of a rocker arm having two operative faces for engaging the valve stem, one face leaving a relatively considerable clearance between itself and the valve stem, a shaft carrying said rocker arm, a scroll cam for traversing said arm axially along said shaft to bring one or other of said faces into operation, a spring around the shaft opposing said traversing movement, 100

and means for limiting the movement of the rocker arm in a direction to allow of the closure of the inlet valve.

2. In internal combustion engines of the compression ignition type, the combination with each inlet valve of a rocker arm for operating said valve having two operative faces side by side for engaging the valve stem, one face leaving a relatively considerable clearance between itself and the valve stem, a shaft carrying said rocker arm, a spring around said shaft holding the rocker arm in a position in which the face thereof leaving a minimum working clearance between itself and the valve stem is in service, a spindle, a scroll or face cam upon said spindle adapted to engage said rocker arm and move it axially along its shaft to bring into service the face with a considerable clearance between itself and the valve stem, the said spindle being shaped either to obstruct the movement of the rocker arm in a direction which allows of the closure of the inlet valve or to clear such arm, and a handle upon said spindle adapted in one position to allow one face of the rocker arm to be in service, in another position to cause the other face to be in service and in a third position to prevent the closure of the inlet valve.
- 30 In testimony whereof we have signed our names to this specification.

JOSEPH GARDNER.
